UNITED STATES PATENT OFFICE.

ALBERT E. PAGE, OF BROOKLYN, NEW YORK, ASSIGNOR TO SCOTT & WILLIAMS, INCORPORATED, OF BOSTON, MASSACHUSETTS, A CORPORATION OF MASSACHUSETTS.

YARN-HOLDING DEVICE FOR KNITTING MACHINES.

Application filed June 21, 1917. Serial No. 176,075.

To all whom it may concern:

Be it known that I, ALBERT E. PAGE, a citizen of the United States, and resident of the borough of Brooklyn, in the city and State of New York, have invented new and useful Improvements in Yarn-Holding Devices for Knitting Machines, of which the following is a specification.

This invention relates to yarn holding devices, one specific use of the mechanism here-
 10 in illustrated being to receive, hold and deliver, if again inserted, the ends of yarns withdrawn during the operation of a knitting machine.
 15 Production of knit articles by automatic machines often requires changes of the yarn being fed to the needles at different times in the production of the article, and when the yarn is so changed that yarn which is with-
 20 drawn is clamped or held in a convenient place for reinsertion, and is usually severed between the holding means and the place where it leaves the fabric. Additional yarns, as for spliced or thickened places, may also
 25 be entered upon the needles and again with-
 drawn, necessitating means to hold the with-
 drawn end. Automatic yarn feeding and severing devices for these purposes are well known in the art, and form no part of my
 30 present invention, which relates to the de-
 vices cooperating with the yarn-feeding de-
 vices to hold the withdrawn ends. Heretofore some form of mechanically actuated clamp positively opened to receive the yarn
 35 has been employed for this purpose in the best practice. These devices necessitate use of an operating connection difficult to ar-
 range on many types of machine without adding elements of complexity to machines
 40 already notoriously complex. Such me-
 chanically actuated clamps are moreover un-
 certain in operation, the opening of the clamp late in the operation upon reinsertion of a yarn withdrawn early in the operation,
 45 in order to receive the yarn for which the re-
 inserted yarn is to be substituted, often per-
 mitting the reinserted yarn to drag all of the other yarns out of the clamp. Repeated

opening of the clamp permits the idle yarns between their yarn-guides and the clamp to 50 slacken so that accurate reinsertion of an idle yarn is not possible. When it is necessary to apply a take-up or heavy tension to any of the yarns, it has heretofore been impracticable to retain the end of such yarn 55 without providing means either to lock the take-up out of action or release the tension on that yarn.

This invention provides means for avoiding the above mentioned difficulties, one ob- 60 ject being to provide a continuously effective holding means adapted to receive the withdrawn yarn and maintain a tension upon it even when receiving additional yarns, and another object being to avoid the 65 creation of slack between the holding means and the operated yarn-guide. Other objects are to enable a yarn under take-up strain or tension to be effectively held without inter-
 70 mitting the action of the take-up or tension device; to avoid the necessity for a mechanical connection to the yarn-holding means, and to provide a simple and inexpensive de-
 vice automatically operating effectively to take and hold a large number of different 75 kinds of yarns upon the motion against the device of the yarn to be held.

In the accompanying drawing,

Figure 1 is a fragmentary plan of a circu- 80 lar knitting machine showing the latch-ring, needles, yarn feeding and yarn severing de-
 vices of an existing type of machine in use with my new devices;

Figure 2 is an elevation in section on line 2—2 of Fig. 1, parts being broken away; 85

Figure 3 is a diagram view similar to Fig. 1, illustrating successive positions taken by inserted yarns;

Fig. 4 is a diagram plan;

Figure 5 is an enlarged side elevation of 90 the spring clamp unattached; and

Figures 6 and 7 are respectively enlarged side and front elevations of the clamp showing the positions taken by said clamp and yarns.

In one specific embodiment of the inven-

2

tion, a circle of needles n , a latch-ring 550, and movable yarn guides 1, 2, 3, 4 and 5, a yarn-severing device 6, and an internal plate 7 supported within the needles and upon which yarns withdrawn from action are received and guided or severed, may be as shown and as in the prior art. The machine illustrated comprises the usual or any suitable automatic devices for actuating the yarn guides 1, 2, 3, 4, 5, and the yarn-severing device 6 at predetermined times to withdraw one or more yarns from knitting and to insert in its or their places another yarn or yarns. As usual, the yarn inserted is placed upon the needles at a point ahead, in the direction of their travel, of the place at which the yarn withdrawn leaves the needles. If the needles are the rotary element, their direction of travel may be that of the arrow a , Fig. 1. On the upper surface of the plate 7, and preferably in a flat depression 8 formed therein I attach a yarn holding device 10 in a position to receive yarns such as yarn y^4 , Fig. 1, when they are withdrawn from the needles, said yarns encountering the device 10 by reason of the relative motion of the needles. When the direction is that indicated, referring to Figs. 1, 2 and 4, the device 10 is positioned on the left-hand side of the center of the machine at a point following the yarn feeding point defined by an active yarn-guide, for instance as shown at 3 in Fig. 1, and between said active yarn-guide and the severing device 6. The plate 7 carrying the device 10 may be positioned relatively to the latch ring 550 by any suitable bracket or connection, such as the connections 9.

Within the genus comprised by my invention the device 10 is capable of many modified forms, but I have herein illustrated the said device as a thin plate spring having a yarn-receiving arm 11 and an attaching arm 12 angularly disposed in a horizontal sense with respect to each other, the body of the device 10 also comprising a yarn-detaining projection 13 projecting toward the yarn feed point, and defining on either side thereof notches c and d , respectively to position for holding yarns approaching the device 10 at different angles and, if desired, under different conditions of tension, whether or not said yarns are of similar or widely different sizes.

A part of the arm 11 is bent upwardly from the plane of the body 10 and the greater part of its own extent to form in the midst of the length of the arm 11 and preferably near the extremity thereof, a rocking point e at the convexity so formed on the under side of the arm 11. The body 10 is flat, and the projection 13 may be in the plane of the body 10 or be bent slightly downward.

The arm 12 is bent slightly at f , the bend

, being at a line preferably including the point e or passing near it.

In use the structure 10, 11, 12 is attached on the plane surface 8 by the screw 15 in a hole in arm 12. The body 10, the greater portion of the arm 11 and the greater portion of the arm 12 normally rest on the surface 8 by spring pressure which may be varied by tightening or loosening the screw 15.

A yarn entering under the arm 11 may 75 lift said arm by bending it upward without disturbing the position of the part of the device near the juncture of said arms. The edge of the device 10 as shown below in Fig. 1 and toward the observer in Fig. 7, is spring 80 held toward the plate 8 by the resilience of arm 12, and yielding at said arm 12, for instance at the bend *f*, will permit the body of the device to be lifted away from the surface 8 without lifting the rocking point *e* 85 from its contact with the surface 8. These properties in the device are functionally useful as will presently appear.

The rocking point *e* and the arm 11 constitute a tension device adapted to receive a yarn swept past it at a point comparatively near the circle of needles, and nearer the circle of needle than the region of the holder 10 surrounding the notch *c*, in which the yarns *y* from the yarn guides 1, 2, 3, 4, 5 normally rest. The yarns *y* normally rest in the notch *c* by reason of the fact that they are withdrawn to a position elevated with respect to the plane 8. Such yarns therefore encounter the projection 13 when any one of the yarn guides 1 to 5 has been elevated to withdraw its yarn, and when the withdrawn yarn has swept beneath the arm 11 and reached the notch *c*. Further motion of the needles *n* may then cause the yarn to be severed at the device 6, or in some cases to float in a central position, if the machine is of another usual type than that shown. Yarns may accumulate in the notch *c* to the extent necessary to accommodate all of those withdrawn without lifting the rocking point *e* from the surface 8.

If it is desired to feed a different kind of yarn, for instance a thicker or thinner yarn, as y^{14} , this may be and is in practice often effected by feeding said yarn at another place than that of the yarn-changing yarn guides 1, 2, 3, 4, 5. As shown, a vertically movable feed-guide 20, which may be automatically movable and which forms no part of my invention, may be employed at the position shown in Fig. 1 for this purpose. For some uses, the yarn y^{10} may be heavily tensioned or be subjected to the action of a spring take-up. When, by the elevation of the guide 20, the yarn y^{10} is withdrawn from the needles, it passes about the various obstructions above the plate 7 and finally enters under the arm 11 and may be severed at the severing device 6. But the yarn y^{10} 130

reaches the holding device 10 at a flatter angle than the yarns y . The relative motion therefore enables the yarn y^{10} to be swept under the accumulated yarns y in the notch 5 c , under the projection 13, and into the notch d .

As will be readily understood from inspection of Figs. 1, 6 and 7 and the above description of the holder 10, such yarn y^{10} 10 may be a thicker yarn than any of the yarns y , and still fail to lift the body of the device 10 at its engagement with the yarns y in such a manner as to release any of them. The tendency of the spring device 10, 11 and 15 12 is to depress itself into contact with the surface 8 at all points, and if yarns in the notch c are thicker than those in the notch d or vice versa, the spring device will merely pivot about the thickest obstruction under 20 it and maintain tension on the other yarns. This action of the device permits any of the yarns to be operated under a tension which, if the clamp were mechanically opened or bodily moved away from the surface 8, would release said yarn and cause it to be pulled back through its yarn guide. It is not essential that the yarn y^{10} or other 25 yarn intended to be positioned in the notch d should be fed from the point 20, since any 30 position causing said yarn to reach the device 10 at a vertical angle with surface 8 substantially more acute than the angle of the other yarns y will suffice to carry said 35 yarn under the yarns y held in the notch c without disturbing the holding of yarns y . For instance, as indicated on the diagram, Fig. 3, a yarn y^{11} may instead of or in addition to the yarn y^{10} be fed from a guide 21 in advance of guide 20. It will be observed that the operation of the device 10 40 with respect to opening and closing to selectively position the different kinds of yarns is brought about by movements of the device 10, 11, 12 effected by the movement against 45 it of the yarns themselves, and is independent of any actuated mechanical connection.

The constantly active tension device comprised of the arm 11 positioned as above described at a point e nearer the needles than 50 the holding points c or d for the idle yarns, and within the segment defined by the newly fed needles and a chord in the vertical plane of any of the held yarns, see Fig. 4, enables 55 the device as a whole to operate in a manner improved over the function of any yarn holding clamp with which I am familiar.

Referring now to Fig. 3, said figure shows the successive positions of a hitherto idle 60 yarn y entered by the yarn guide 3 at the point n^1 , the points n^2 , n^3 , etc., to n^7 indicating successive following positions of the entrance point n^1 . The end of the yarn y in 65 said guide 3 being held under the clamp 10 first presents a taut run y' . But the relative motion of the needles when the point n^1 in

the needles reaches the place n^2 has slackened the yarn as shown. When the place n^3 is reached, this slack has begun to bend into a bight or loop; when n^4 is reached, this bight or loop is about to pass under the rock- 70 ing point e of the arm 11 and so to form a bight y^2 tensioned on one leg by the original hold of the device 10 and on the other leg by its new passage under the tension arm 11. When the entrance point passes from 75 n^5 to n^6 to n^7 , this tensioned bight y^2 is drawn smaller and is then extinguished, the yarn end y' passing out from under the holder 10 when the entrance point passes at a place between the points n^6 and n^7 . 80

When the yarn y' so finally leaves the holder 10, it has passed the vertical plane defined by any of the idle yarns. The bight y^2 , unless it was formed in that yarn y which was last entered into the clamp or holder, is 85 necessarily in frictional contact with the group of yarns y held under the holder 10; and the rapid withdrawal of the bight or loop y^2 thus in frictional contact with the group of clamped yarns has been found to 90 exercise a marked tautening effect on the clamped yarns, gradually pulling the free ends held under the clamp further under the clamp and tightening the yarn between the elevated yarn guides and the clamp. This 95 action is rendered more effective by the twisting together of the yarns y , always occurring more or less during the occupation of the clamp or holder 10 by such yarns. When the yarn y^{10} is reinserted upon the 100 needles after having once taken the position shown in Fig. 3, this yarn also is thrown into a bight y^8 which has a still more marked 105 tightening effect on the clamped yarns y , as will be apparent from inspection of Figs. 2 and 7.

The best position of the device 10 within the segment defined by the plane of an idle yarn and the moving needles will vary 110 slightly with changed dimensions of the parts, but it is desirable that a sufficient distance should separate the device 10 and the feeding point F, Fig. 4, to form from an inserted yarn an end long enough to produce a bight y^2 of substantial dimensions. 115

What I claim is:—

1. A yarn-clamp for knitting machines, consisting of a plate spring having angularly disposed arms, a body adapted to rest on the yarns having a yarn-detaining projection at the junction of said arms, and means for attaching one of said arms at an extremity thereof to a surface against which the yarns are to be clamped. 120

2. A knitting machine having therein 125 means to feed yarns and to withdraw said yarns to different positions, in combination with a spring yarn clamp having notches separated by a yarn-detaining projection adapted to pass into one of said notches a 130

yarn or yarns withdrawn to a certain position and to retain in the other notch yarns withdrawn to other positions.

3. A spring yarn-clamp comprising angularly disposed arms one of which is bent to form a rocking point and the other of which is adapted to be attached to a supporting surface to yield resiliently trans-

versely to the plane of said arms and away from said surface, whereby the body of said device may take over and hold yarns of different size without lifting said rocking point from said supporting surface.

Signed by me at New York, N. Y., this second day of March, 1917.

ALBERT E. PAGE,
